UNITED STATES PATENT OFFICE.

HERMAN COSKI, OF CHICAGO, ILLINOIS.

LATCH FOR TRAVELING BAGS.

1,403,014.

Specification of Letters Patent. Patented Jan. 10, 1922.

Application filed April 11, 1921. Serial No. 460,384.

To all whom it may concern:

Be it known that I, HERMAN COSKI, a citizen of the United States, residing at Chicago, in the county of Cook and State of Illinois, have invented a new and useful Improvement in Latches for Traveling Bags, of which the following is a specification.

My invention relates to traveling bags and cases, and more particularly to means for securing or retaining the two sections or edges of the closure in co-operative relation with each other so that accidental unlatching of the same is not liable to occur.

The present structure has been especially designed for use in connection with what are generally known as "Gladstone bags," which consist of two compartment members that are hinged together at their lower edges and usually divided by a centrally disposed partition which permits the opening of one compartment without disclosing the contents of the other compartment. However, it will be understood that the structure herein disclosed is well adapted for use in connection with other types of traveling bags, suit-cases, and similar impedimenta.

In the use of traveling-bags of the Gladstone type, the weight of the articles packed or stored in the compartment to which the handle is secured, when carried or suspended by the handle, will cause a slight bowing upwardly of the frame surrounding the open edge of this compartment, but the most serious objection inherent in such bags is that the weight of the articles in the opposite compartment invariably causes a sagging of this compartment, due to the use of a double-pintle hinge for connecting the compartments with the result that the edge of said compartment will pull away from the opposite compartment edge with which it is supposed to fit, and not infrequently parts of the end latches, and sometimes the lock itself, becomes disengaged so that the said compartments will disengage or be opened and spill the articles. With the ordinary forms of latches, which are in general use, no provision has been made, so far as I am aware, to prevent the release of the parts due to this sagging or pulling away of the compartment unattached to the handle. It is, therefore, an object of my invention to provide a latch that will effectively retain

and latch the meeting edges of the two compartments of a traveling bag so that the section to which the handle is attached will support the other compartment and prevent the sagging or pulling away of the latter from the former. Another object is to provide a latch that will not release the compartments excepting when intentionally operated, and which is constructed so that the greater the pull made on the carrying compartment by the other compartment the firmer the latch will hold and the less the liability of the parts to accidentally open or release. Also, I have provided a latch structure that permits the frame of the carrying compartment to support the adjacent frame of the other compartment. A still further object of my invention is the provision of means for facilitating and effectively latching the partition wall to one of the compartment frames whereby the liability of the same snapping loose is reduced to a minimum. Still further objects will be apparent to others after an understanding of my invention is had, and I prefer to carry out my present improvements in substantially the manner hereinafter fully described, and as more particularly pointed out in the claims.

Reference will now be made to the accompanying drawings that form a part of this specification, in which—

Figure 1 is a perspective of a traveling bag of the Gladstone type showing the application of my improvements thereto.

Figure 2 is a fragmental detail enlarged showing the plate for releasably securing the partition wall to the carrying frame of the bag.

Figure 3 is a transverse sectional view taken on line 3—3, Figure 2.

Figure 4 is a similar view taken on line 4—4, Figure 2.

Figure 5 is a fragmental detail of a corner of the partition wall showing the element that coacts with the structure, shown in Figure 2.

Figure 6 is a transverse sectional view taken on line 6—6, Figure 5.

Figure 7 is a longitudinal side view of my improved latch element which is secured to the carrying frame of the bag.

Figure 8 is a top plan of the structure shown in Figure 7, and

Figure 9 is a similar view of the element secured to the other frame of the bag and in position to be inserted into the latch.

Figure 10 is a vertical longitudinal section taken on line 10—10, Figure 8, and

Figure 11 is a transverse vertical section on line 11—11, Figures 8 and 9, showing the two parts of the latch in assembly after the compartments have been brought together in closed position.

In the accompanying drawings, I have employed the same reference characters to designate like parts throughout the several views, and by reference to Figure 1 thereof, it will be seen the traveling bag to which I have applied my improvement consists of two substantially similar compartments A and B hinged along their lower edges so that the bag may be conveniently opened in a flat manner to afford ready access to the interior thereof. The edge portions of these compartments which are adapted to be brought together when the bag is closed are each reinforced by a suitable covered frame. The frame C for compartment A, being the supporting or carrying frame, is of L-shape or angular cross-section and is considerably heavier than the somewhat smaller and lighter frame D extending around the edge of compartment B. A carrier or handle E is mounted upon the frame C about midway the length of the portion thereof farthest from the hinge, and the casing of the usual lock F is also mounted upon frame C to act in conjunction with the usual loops G that register therewith upon frame D. A partitioning or dividing wall H is flexibly secured to the hinged portions of compartments A and B and is of such dimension that its edges will lie against the inwardly projecting flange of frame C when in closed position and for the purpose of securing this wall H in position, and to retain it against this flange of frame C, I have provided the structure, illustrated in Figures 2 to 6 of the drawings.

In these figures, it will be seen that I have provided partition H at its corner with one of the elements of a separable fastener, preferably the socket member 15 of the well known glove fastener type. The coating or stud member 16 of the fastener is secured to a lobe or projection 17 of a segmental crescent shaped plate 18 mounted on frame C in the corner of compartment A. There are two sets of fasteners and two plates 18 positioned as above mentioned, and I prefer to attach the plates by means of lateral tangs or spurs 19 projecting from the edges of the blanks from which plates 18 are formed and which are bent under the metal of frame C around the edges thereof to securely mount the plates in position. The curvature of the edges of the plate substantially corresponds with the curvature of the inwardly pro-

jecting flange of the frame, and when the partition wall H has been attached thereto by fasteners 15—16 the edge of the partition will lie snugly against the frame in a neat manner and in a snug fit.

Mounted upon the outside of frame C farthest from the hinge and adjacent the corners are the two latching casings that coact with loops carried by frame D, and as these structures are substantially duplicates, 75 but one will be described. This latch structure comprises an elongated base or body 20 that is reduced in height adjacent each end to provide ears 21 through which rivets or other devices are passed to secure the body to frame C. A bar or arm 22 is pivotally mounted at one end by a pintle 23 on the upper portion of the body adjacent one end thereof, and said arm at its end opposite its pivot extends out over the reduced 80 portion 21 to provide a lip or finger grasp 24 by which the arm may be raised or lowered, whenever desired. Projecting downwardly from the underside of arm 22 is a latch bolt or pin 25 that is preferably 90 straight and is of round cross-section so that it may pass or be projected through a circular opening in the adjacent upper portion of the body or base 20 to engage the coacting element of the latch that is carried by the 95 compartment member B of the bag. This element comprises a plate 26 that projects laterally out from the edge of frame D of compartment B and is provided with a recess or aperture 27 in its outer portion into 100 which latch bolt 25 enters to retain and support the compartment B. Plate 26 may be of substantially L-shape, as shown, the lateral arm 28 whereof passes through the material of the bag, as seen in Figure 11 of the 105 drawings, and is secured to the metal forming frame D by a rivet 29, or otherwise. In order that plate 26 may enter the body or base 20, I have provided the side of the latter facing plate 26 with an elongated opening 110 or slot 30, and for the purpose of protecting the material with which the bag is covered from injury by plate 26 moving in and out of opening 30, I have interposed a relatively thin strip of metal 31 between the bottom of 115 the base or body 20 and the adjacent portion of the bag.

In operation, when the two compartments of the bag have been brought together and closed plate 26, which is upon compartment 120 B, will be disposed above the frame of compartment A upon which handle E is secured, and when the bag is lifted by the handle the compartment B is retained in close relation to frame C and is prevented from sagging or dropping down because the plate will be resting upon the same frame that supports compartment A. I prefer to make latch bolt 25 long enough to enter an aperture 32 in plate 31, and frame C after pass- 125 130

ing through plate 26 so that these parts will assist the bolt in retaining plate 26 in latched position, and in order to prevent said plate working loose or accidentally 5 pulling itself from the bolt, I have provided the latter with a notch or groove 33 upon its segment farthest from opening 30 through which plate 26 is inserted or withdrawn.

From the foregoing, it will be seen I have 10 provided an effective means for securing the two parts of a traveling bag together, and at the same time have successfully overcome the inherent tendency of one of the parts to sag or pull away from the other when 15 heavily loaded. It will be understood that the drawings are, in a sense, merely dia- 20 grammatic for the purpose of illustrating one type of embodiment of my invention, which may be modified to suit the structure to which the same is applied.

What I claim as new is:

1. In a traveling bag, a frame forming one of the edges of a compartment, a second frame hinged thereto and coactable therewith, a base mounted upon said first frame and having an opening upon one of its sides, an arm hinged at one end to said base, a latch bolt depending from said arm and projected through said base by the 25 movement of said arm, and an apertured element carried by said second frame, said element to be thereby inserted through the opening in said base above the first frame and through which said bolt is projected by 30 the movement of said arm.

2. A traveling bag having a frame comprising two elements hinged together so as to lie one inside of the other in folded or closed position, a casing secured to the outer 40 of said elements provided with intersecting openings respectively on the side and top, a recessed arm secured to the inner of said frame elements and entering the lateral opening in said casing when said frame elements are in closed position, and an arm 45 hinged at one end of the casing, a latch bolt

depending from said arm and entering the top opening in said casing and extending through the recess in said arm when in closed position.

3. In a traveling bag, a frame forming one of the edges of a compartment, a second frame hinged thereto and coactable therewith, a base mounted on said first frame, a recessed element carried by said second frame and extending into coactive relation with said base, and a latching device brought into latching position within said base by the movement of said element in which position said device engages said recessed ele- 50 55 60

4. A traveling bag having a frame comprising two elements hinged together so as to lie one inside the other in folded position, a casing secured to one of said frame elements, an arm secured to the other of said frame elements and extending into coactive relation with said casing when said frame elements are in closed position, a member 65 movably mounted on said casing, and a latch bolt movable longitudinally into and out of engagement with said arm by the movement of said member.

5. In a traveling bag, a frame forming one of the edges of a compartment, a second frame hinged thereto and coactable therewith, a base mounted on said first frame, a recessed element carried by said second frame and extending beyond said first frame and into coactive relation with 70 75 80 said base, an element movably mounted upon said base, and a latching device brought into latching position and into engagement with said base by the movement of said element.

Signed at Chicago, county of Cook and State of Illinois, this 9th day of April, 1921.

HERMAN COSKI.
